UNITED STATES PATENT OFFICE.

EDGAR H. CLARK, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed February 7, 1919. Serial No. 275,616.

To all whom it may concern:

Be it known that I, EDGAR H. CLARK, a citizen of the United States, residing at New York, in the county of New York, State of 5 New York, have invented certain new and useful Improvements in Telephone-Exchange Systems, of which the following is a full, clear, concise, and exact description.

This invention relates to telephone systems employing automatic switches.

The present invention is an improvement over a system disclosed in an application filed by me on October 4, 1918, Serial No. 256,841, and has for its object the provision 15 of an improved signaling system in which indicating devices are controlled over a pair of wires by trains of impulses of various characteristics.

In its more specific embodiment, the present invention is employed in an automatic telephone system in which calling lines terminating in a semi-automatic telephone exchange may be connected to called lines terminating at a manual exchange. In such a 25 system an operator at the semi-automatic exchange after connecting her answering cord to the calling line, sets one or more automatic switches under the control of a sending device to extend the calling line to an operator's position at the manual exchange.

Since there is no verbal communication between the two operators, there must be means for indicating to the operator at the manual exchange the number of the wanted 35 line. In the present disclosure such number is indicated by sets of lamps, a set of lamps being provided for each digit or character of the wanted number. These lamps are selectively operated in response to the sending device.

One feature of the invention consists in the control of an indicating device by trains of impulses of varying characteristics, the separate impulses being of like character.

45 This and other features of the invention will appear from the accompanying drawings and description together with the appended claims.

The drawing with Fig. 2 placed below and 50 with Fig. 3 placed to the right of Fig. 1, diagrammatically illustrate a portion of a telephone system employing the present invention. Fig. 1 shows a calling subscriber's substation and line with brushes of the dis- 55 tinct selector at the semi-automatic opera-

tor's position, the calling plug and jack at the manual operator's position and a called subscriber's substation apparatus and line. Within the small dotted rectangle at the left-hand side of Fig. 1 there are shown brushes 60 of a cord finder switch which operates to connect an idle sending device to a cord circuit which has been connected to the called line. Within the larger dotted rectangle at the right-hand side of Fig. 1 there are shown the 65 operator's key set and the registers of a sending device for controlling the transmission of impulses to the number indicating device. Within the dotted rectangle in the middle of Fig. 1, there is shown an impulse 70 transmitting device which under the control of the registers transmits various combinations of impulses to actuate the number indicating device. In Fig. 2 there are shown the various relays which control the lighting 75 of the proper stations lamp as well as the switching relays which operate to control the actuation of the thousands, hundreds, tens and units indicating devices in the proper sequence. Fig. 3 in its lower right-hand corner shows the lamp controlling relays for indicating the thousands digit, in the lower left-hand corner of Fig. 3 the hundreds digit, at the upper left-hand corner of Fig. 3 the tens digit and at the upper right-hand corner 85 of Fig. 3 the units digit.

In this disclosure the showing of the apparatus and circuits for selecting the manual operator's position has been abbreviated, but they may be of the character of the system disclosed in the patent to Lundell, No. 1,168,319 of January 18, 1916, or it may be 90 similar to the system shown in applicant's Patent No. 1,334,735, issued March 23, 1920.

The trunk selecting switch referred to in 95 the description may be of the type illustrated in the patent to Craft and Reynolds, No. 1,123,696, of January 5, 1915, although it will be readily understood that any automatic selector switch can be employed in 100 this system without departing from the spirit of the invention.

In the description reference is made to sequence switch registers, the construction of which may be similar to that shown in the 105 patent to Reynolds and Baldwin, No. 1,127,808 of January 9, 1915.

In general the present system comprises a set of operator's keys which control sequence switch registers, all of which are 110

shown in the dotted rectangle at the right of Fig. 1. A device for sending impulses as determined by the sequence switch registers is shown in the upper left hand corner 5 of the dotted rectangle of Fig. 1 and an arrangement of relays for receiving these impulses is shown in Figs. 2 and 3.

In Fig. 2 there are shown two relays 201 and 202 which respond directly to the transmitted impulses. These relays in turn control the combination of two relays 207 and 209 which have a peculiar interaction as will be hereinafter more fully explained. A set of relays such as 206 and 210 is provided 15 for each one of the digits of the called number. These relays are controlled by the interaction of the relays 207 and 209.

There is provided a set of indicating lamps for each one of the digits of the called number, each set of lamps being controlled by a 20 set of controlling relays A, B, C and D. As shown in Fig. 3, the set A', etc. controls the thousands lamps, the set A², etc. controls the hundreds lamps, the set A³, etc. controls the 25 tens lamps and the set A⁴, etc. controls the units lamps. As shown in Fig. 2 the set A etc. controls the stations lamps.

The impulses transmitted by the device controlled by sequence switch 114 in Fig. 1 30 are in the nature of a code, these impulses being in one train as the sequence switch 114 moves from one position to the next until it has finally reached normal position again.

35 The impulses for controlling the indication of any one digit consists of four stages and the whole set for the selection of all of the indicating lamps are merged into one continuous train of twenty stages. The im- 40 pulses consist of grounding neither, either one or the other or both of the two lines extending from the sending device at the semi-automatic operator's position to the receiving device at the manual operator's position. The second and fourth stages in each 45 train of impulses are necessarily always a grounding of the ring side of the line. The first and third stages are either a grounding or a non-grounding of the tip side of the 50 line. The second and fourth stages may also consist in the grounding of both the ring and tip sides of the line.

The various combinations are shown dia- 55 grammatically in two tables as in Fig. 2, one marked "numerical" and the other "station". Thus, for instance, the train of impulses representing the digit 7 consists in the first stage of the grounding of the tip side of the line, the second in the grounding of both the 60 tip and ring sides of the line, in the third stage of the grounding of neither the tip nor the ring, and in the fourth stage of the grounding of the ring side of the line. Similarly, the trains of impulses representing the 65 other digits and stations characters are built

up with various combinations of such connections.

As will hereinafter appear the lamp controlling relays A, B, C and D are only energized when the tip side of the line is grounded. Thus, for instance, when the train of impulses representing the digit 7 are transmitted, the relays A and B only will be energized and the relays C and D will remain unenergized. The stations code, since a smaller number of selections is to be made, never contains a grounding of the tip side of the line in the fourth stage, and therefore only three lamp controlling relays A, B and C are provided, the last stage being merely for switching purposes.

The particular action of the relays as effected by the sending of these trains of impulses will be more fully explained hereafter.

It is believed that the invention will best be understood by describing the method of establishing a connection from a calling substation as shown at 101 to a called station as shown at 102. When the calling subscriber removes his receiver from his switchhook, a signal (not shown) is lighted at the semi-automatic operator's position. This operator thereupon connects the cord circuit conductors 103 and 104 to the calling line manually or by any other suitable means. As soon as the semi-automatic operator has connected the cord circuit to the calling line, a cord finder whose brushes are indicated at 105 and 106 operates to connect an idle sending device to the cord circuit taken for use.

When the semi-automatic operator connects the cord circuit to the calling line, she ascertains the number of the wanted subscriber and proceeds to set up this number from the keyboard of her sending device.

We will now assume that the wanted number is 4567-W. The operator will then depress the corresponding thousands, hundreds, tens, units and stations keys, in response to which the associated sequence switch registers will be moved. The stations register 109 will come into position 5, the thousands register 110 in position 4, the hundreds register 111 in position 5, the tens register 112 in position 6, and the units register 113 in position 7.

It will be assumed that the automatic trunk selecting switch whose brushes are indicated by the numerals 107 and 108 has been set to select the proper trunk for connecting the calling subscriber with the manual operator's position at the office in which the wanted line terminates. It will also be assumed that the sequence switch of this trunk selecting switch has been moved into position 11.

After the sending device has been set, and when the trunk selecting switch has been op-

erated to extend the calling line to the manual operator's position at the desired office, the sequence switch associated with the cord finder will be in position 7 where a circuit 5 will be established to energize the relay 117. This circuit may be traced from ground, sequence switch cam 116, winding of relay 117, sequence switch cam 118 (position 1), brush 105, sequence switch contact 119, brush 108, lower armature and back contact of relay 120, lower winding of repeating coil 121, winding of relay 123 to grounded battery. Relays 117 and 123 are operated by current flowing over this circuit. Relay 117, by the 15 attraction of its armature, closes a circuit from ground, armature and front contact of relay 117, winding of relay 115 to grounded battery, whereby relay 115 is energized. At the front contact and armature of relay 123, a circuit is closed from ground, through the left-hand back contact and armature of relay 125, the lamp 126 to grounded battery. Lamp 126 in lighting indicates to the manual operator that a call is awaiting attention, 20 and also indicates the trunk over which the call has been extended. The manual operator thereupon depresses key 127 to associate the number indicating device with the trunk over which the call has been extended.

Upon the depression of key 127, a circuit is closed from ground, winding of relay 120, contact of key 127, conductor 128, winding of relay 200 to grounded battery. Relay 200 attracts its armatures to apply ground to the 25 various controlling leads of the number indicating device. At the same time the relay 120 attracts its armatures, and at the lower armature and back contact interrupts the energizing circuit of relay 117. When this relay deenergizes, it closes a circuit from ground, through its armature and back contact, the armature and back contact of slow-to-release relay 115, magnet of sequence switch 114 to grounded battery, to move the 30 sequence switch 114 out of position 1, whereupon it will, under the control of its master contact 124, rotate through its various operating positions back to position 1, during which a complete set of impulses is transmitted to the relays 201 and 202.

In accordance with the number which we have assumed will be indicated, that is, 4567-W, impulses will be sent over the two conductors 134 and 204 to the relays 201 and 55 202, respectively, in accordance with the following table. As has been hereinbefore pointed out, the train of impulses consists of twenty stages, in each even one of which the ring side of the line of the conductor leading 60 to brush 105 will be grounded. The other side of the line or that leading to the brush 106 may be grounded at any one of the stages. In the first column, the stages are numbered numerically, from 1 to 20. In the 65 second column, the position of the sequence

switch during that particular stage is indicated. In the third column, the stages in which the ring side of the line is grounded is indicated, and in the fourth column the stages in which the tip side of the line is 70 grounded are in turn indicated by the letter G.

Stage.	Position of sequence switch.	Ring side of line.	Tip side of line.

From this table it will be evident that in every even stage the relay 201 will be energized, and in every odd stage it will be deenergized. It will also be evident that relay 202 will be energized only when the tip side of the line is grounded, which may occur in any stage. Thus, for instance, in the first stage, relay 202 will be energized, but relay 201 will not be energized.

The action of the pair of relays 207 and 209 is controlled by the relay 201. Since the relay 201 becomes energized in every even position and deenergized in every odd position, there will be a recurring application of ground on the conductor 203, extended thereto from the conductor 208 through the right-hand armature and front contact of relay 201. It should be noted that the first application of ground to conductor 203 results in the energization of relay 207. The first removal of ground therefrom results in the energization of relay 209. The second application of ground thereto results in the deenergization of relay 207 and the second removal of ground therefrom results in the deenergization of relay 209. Thus, in the second stage, relay 207 will be energized. In the third stage relay 209 will be energized. In the fourth stage relay 207 will be deenergized. In the fifth stage relay 209 will be deenergized, and this action and interaction of relays 207 and 209 will continue throughout the sending of the impulses.

This is accomplished as follows: In the second stage relay 201 by applying ground to the conductor 203, extends this ground through the left-hand armature and back contact of relay 209, the winding of relay 207, the left-hand winding of relay 209 to battery and ground. The left-hand winding

of relay 209 is marginal and the current flowing through these two windings in series is insufficient to cause the energization of relay 209, but does cause the energization of relay 207. Relay 207, in becoming energized, extends the ground on conductor 208 through its inner right-hand armature and front contact to the right-hand winding of relay 209 which thus becomes short circuited as long as the ground is applied to conductor 203. When the third stage is reached, and relay 201 becomes deenergized and the ground is removed from the conductor 203, a circuit extending from ground at the inner right-hand armature of relay 207 may be traced through the right-hand winding of relay 209, the winding of relay 207, the left-hand winding of relay 209 to battery and ground. Current traveling through this circuit is sufficient to cause the energization of relay 209, and to cause the continued energization of relay 207, whereby the relay 209 becomes sufficiently energized to attract its armatures. In the fourth stage, relay 201 is again energized and thereby applies ground to the conductor 203. In this manner the winding of relay 207 and the right-hand winding of relay 209 are short-circuited and the left-hand marginal holding winding of relay 209 is kept energized. In this manner relay 207 retracts its armatures. When now in the fifth stage, the relay 201 becomes deenergized, and the ground is removed from the conductor 203, neither winding of relay 209 being now energized, the relay retracts its armatures. The actions and interactions of relays 207 and 209 control sets of counting relays such as 206 and 210, for the stations lamp controlling relays, and the set 211, 213 for the thousands lamps controlling relays. This is done in the following manner: Upon the first energization of relay 207 which takes place, as hereinbefore described in the second stage, a ground is extended from the conductor 208 through the outer right-hand armature and front contact of relay 207, the inner left-hand armature and back contact of relay 210, the winding of relay 206, to battery and ground. Relay 206 is energized in this circuit and in attracting its armatures extends a ground from conductor 208, through its inner right-hand armature and front contact to the winding of relay 210, which, however, is short-circuited at this time through the application of ground by relay 207. In the fifth stage, when the relay 209 becomes deenergized, relay 210 becomes energized through the circuit just described extending from conductor 208, the inner right-hand armature and front contact of relay 206, winding of relay 210, winding of relay 206, to battery and ground. In the sixth stage, when relay 207 is again energized, a circuit is extended from conductor 208, the outer right-hand armature and front contact of relay 207, the inner left-

hand armature and front contact of relay 210, the inner left-hand armature and back contact of relay 213, the winding of relay 211 to battery and ground, whereupon relay 211 becomes energized and establishes a potential energizing circuit for relay 213 which becomes effective upon the deenergization of relay 209 in the ninth position. The action and interaction of the relays 209, 207 and the counting relays are clearly shown in the following table. In the first column there is a list of the stages of operation of sequence switch 114, extending from the first stage, back to normal position 1 of sequence switch 114. In the second column the condition of relay 207 is indicated by the letters D and E which indicate respectively deenergization and energization. In the third column the condition of relay 209 is similarly indicated. In the fourth column, there is a list of the counting relays as they are in turn energized. When, for instance, relay 206 becomes energized in the third position, it remains energized until the ground is removed from conductor 208, as will hereinafter be described. 90

Normal position of 114.				

Through the action of relay 202 which is connected to the tip side of the line and extends through conductor 204, the upper armature and front contact of relay 120, brush 107, the sequence switch contact 135, brush 106, the conductor 140 to the register contacts controlled by the sequence switches 109 to 113 inclusive, and thence to sequence switch contacts controlled by the sequence switch 114. As indicated in the first table, this side of the line will be grounded at various times, specifically during the first three of the first four stages. This is seen when it is remembered that sequence switch 109 is placed in position 5, whereby a ground is extended through the sequence switch contact 132 in position 13 of sequence switch 114, which is the first stage, sequence switch contact 131 of sequence switch 109 which is in position 5. Likewise ground is supplied through sequence switch contact 138 in position 21 of 130

sequence switch 114 which is the second stage, through sequence switch contact 137 of sequence switch 109, and likewise through sequence switch contact 141 in position 3¹ 5 of sequence switch 114 which is the third stage, and thence through sequence switch contact 172 in position 5 of sequence switch 109. In a similar manner, conductor 140 is grounded at various stages of operation of 10 the sequence switch 114. The effects of these groundings of conductor 140 are shown in the energization and deenergization of relay 202. As an instance, relay 202 is energized in the first, second and third stages 15 and deenergized in the fourth stage. Upon its first energization, a circuit is established from the grounded conductor 208, the left-hand armature and back contact of relay 201, left-hand armature and front contact of 20 relay 202, the left-hand armature and back contact of relay 207, left-hand armature and back contact of relay 206, left-hand winding of relay A to battery and ground, whereby 25 the relay A is energized. It will thereupon lock up to the ground on conductor 208, through its inner right-hand armature and front contact and two windings in series. In the second stage, relay 202 being energized and relay 201 now being energized, a circuit 30 is extended from the ground on conductor 208, through the left-hand armature and front contact of relay 201, right-hand armature and front contact of relay 202, the outer right-hand armature and back contact of relay 35 209, the right-hand armature and back contact of relay 210, to the left-hand winding of relay B to battery and ground. Relay B thus becomes energized, and in a similar manner to relay A, locks up to the ground 40 on conductor 208. In the third stage relay 202 is energized and relay 201 becomes deenergized. Thus, we have a ground extending from conductor 208, left-hand armature and back contact of relay 201, the left- 45 hand armature and front contact of relay 202, left-hand armature and front contact of relay 207, the outer right-hand armature and front contact of relay 206, the outer right-hand armature and back contact of relay 50 211, the left-hand winding of relay C, to battery and ground, whereupon the relay C locks up to the conductor 208 in a manner similar to relays A and B. In a similar manner, the other lamp controlling 55 relays of the thousands, hundreds, tens and unit sets are energized. A full description of this will be found in my copending application above mentioned. From the description, it will be seen that the one set of 60 impulses is sent over the ring side of the line which may be spoken of as a periodically recurring set of impulses to control the relay 201, and thereby control the actions and interactions of relays 207 and 209, and in turn the action of the counting relays. 65 Another set of impulses which is not periodically recurring is transmitted over the tip side of the line through conductor 204 to control the relay 202. The action of relay 202 plays no part in the control of relays 207 70 and 209, or the counting relays, its sole function being to energize the lamp controlling relays when the proper circuits have been set up through the action of the counting relays. 75

When the sequence switch 114 has returned to its normal position and the relay 209 is finally deenergized, and the said counting relay 221 is energized, the circuits for the lighting of the different lamps are established. Through the outer left-hand armature and front contact of relay 221, a ground is placed on the winding of relay 223 which becomes energized. Through the outer right-hand armature and front contact of relay 219 and the outer right-hand front contact and armature of relay 221, battery is placed on the conductors 311 and 312 for lighting the lamps in the tens and units series. Through the left-hand armature and front contact of relay 217 ground is placed on the conductor 222 for energizing relay 310, which in turn places battery on the conductors 313 and 314, for lighting the lamps in the thousands and hundreds series. Through 95 the inner left-hand armature and contact of relay 200 ground is placed on the common conductor 301 for lighting the lamps in the thousands, tens and units series, and through the outer left-hand armature and contact of relay 310 ground is extended from the conductor 208 through the conductor 315 for lighting the lamps in the hundreds series. 100

The stations lamp W is included in a circuit from battery, the next to the outermost right-hand armature and contact of relay 223, front contact and inner left-hand armature of relay C, the front contact and outer right-hand armature of relay A, the front contact and left-hand armature of relay B 110 to the outermost armature of relay 223 to ground. The thousands lamp 4 is included in a circuit from battery, the outer right-hand armature and front contact of relay 310, the lamp 4, the next to the outermost 115 armature and back contact of relay A', the back contact and outer left-hand armature of relay B', front contact and inner right-hand armature of relay D' to the ground on conductor 301. The hundreds lamp 5 is included in a circuit from battery, the inner left-hand armature and contact of relay 310, the outer left-hand armature and back contact of relay D', the outer left-hand armature and front contact of relay B', the next 120 to the outermost right-hand armature and back contact of relay A', the lamp 5, the front contact and inner left-hand armature 125

of relay B², the next to the innermost right-hand armature and back contact of relay A², the back contact and outer left-hand armature of relay C², the contact and outer left-hand armature of relay 310 to the ground on conductor 208. The tens lamp is included in a circuit from the conductor 311, the inner left-hand armature and front contact of relay D³, the lamp 6, the front contact and 5 next to the outermost right-hand armature of relay A³, the front contact and outer left-hand armature of relay B³, the front contact and inner right-hand armature of relay D³ to the ground on conductor 301. The 10 units lamp 7 is included in a circuit from the conductor 312, the outer left-hand armature and back contact of relay D⁴, the outer left-hand armature and front contact of relay B⁴, the next to the outermost right-hand 15 armature and front contact of A⁴, lamp 7, the back contact and outer right-hand armature of relay D⁴ to the ground on conductor 301. In this manner the lamps indicating the number 4567-W are illuminated.

25 When the operator at the manual exchange pressed the key 127 and the relays 120 and 200 were energized in series, the circuit for relay 123 was opened, whereupon the armature of relay 123 was retracted and the lamp 30 126 extinguished.

As soon as the indicating lamps become illuminated, as herein described, and the operator has the wanted number well in mind, she removes the pressure from key 127, 35 allowing the relay 120 and the relay 200 to become deenergized. She thereupon places plug 161 into the jack 162 of the line No. 4567, and presses the proper ringing key to ring the station W. This action, through 40 means not shown, causes the conductors 103 and 104 to be connected through sequence switch contacts 165 and 164 to the brushes 107 and 108, respectively, whereby the connection is completed and the circuit to 45 brushes 105 and 106 discontinued. The circuit through the substation 101 energizes relays 123 and 167. The circuit through the sleeve of the jack 162 and the plug 161 energizes the relay 125, so that although the 50 lamp 126 is now connected to the front contact of relay 125, its circuit is opened at the back contact of relay 123. At the end of the conversation, when the subscriber at substation 101 replaces his receiver upon its 55 hook and thereby deenergizes relay 123, the lamp 126 will be illuminated to indicate to the manual operator that the conversation has ceased.

When relay 200 becomes deenergized, it 60 removes the ground from conductors 208 and 301, whereby all of the lamp controlling relays which have locked up to the conductor 301 and the counting relays which have locked up to conductor 208 will become de-

energized and the device restored to its normal condition. 65

It will be understood that this disclosure is merely typical of applicant's invention and that its use is not limited to number indicating arrangements in automatic telephone systems or even to telephone systems broadly. 70

What is claimed is:

1. In a signaling system, a plurality of indicators, a signaling circuit comprising 75 two limbs, a progression switch comprising a plurality of relays, means for propagating and transmitting over one limb of said circuit a series of like impulses for successively operating said relays, and means for propagating and transmitting over the other limb of said circuit a second series of like impulses for selectively operating said indicators. 80

2. In a signaling system, a plurality of 85 indicators, a plurality of relays for controlling the operation of each of said indicators, a progression switch comprising a plurality of relays, a signaling circuit comprising two limbs, means for propagating and transmitting over one limb of said circuit a series of like impulses to operate said progression switch relays in succession, and means for propagating and transmitting over the other limb of said circuit a second series of like 90 impulses for selectively actuating said indicator controlling relays. 95

3. In a signaling system, a plurality of indicators, a plurality of controlling relays for each indicator, a progression switch comprising 100 a plurality of relays, means for propagating and transmitting over one limb of said circuit a series of like impulses for causing the successive operation of said progression switch relays, and means for simultaneously propagating and transmitting over the other limb of said circuit a second series of like impulses for selectively operating 105 said indicator controlling relays. 105

4. In a signaling system, a plurality of 110 indicators, a signaling circuit comprising two limbs, two groups of relays, means for propagating and transmitting over one limb of said circuit a series of like impulses for operating all of the relays of one of said groups in succession in a fixed order, and means for propagating and transmitting over the other limb of said circuit a second series of like impulses for operating desired ones of the relays of said other group to 115 control said indicators. 120

5. In a signaling system, a plurality of indicators, a signaling circuit comprising 125 two limbs, two groups of relays, means for propagating and transmitting over one limb of said circuit a series of like impulses for operating all of the relays of one of said groups in succession in a fixed order, and

means for simultaneously propagating and transmitting over the other limb of said circuit a second series of like impulses for operating desired ones of the relays of said other group to control said indicators.

6. In a signaling system, a signaling circuit, a pair of circuit relays, a set of master relays, a plurality of sets of counting relays, a plurality of signal controlling relays, a plurality of sets of signals, means for periodically actuating one of said circuit relays, means responsive thereto for periodically actuating said master relays, means

responsive thereto for operating said sets of counting relays in sequence, means for actuating the other one of said circuit relays, means responsive thereto for actuating said signal controlling relays, and means responsive to said signal controlling relay means and said connecting relay operating means for actuating said signals.

In witness whereof, I hereunto subscribe my name this 30th day of January, A. D., 1919.

EDGAR H. CLARK.
